UNITED STATES PATENT OFFICE.

ALBERT O. ERICKSON, OF JASPER, MINNESOTA, ASSIGNOR OF ONE-HALF TO KNUTE WOLD, OF JASPER, MINNESOTA.

SPRING TOOL.

Application filed January 9, 1926. Serial No. 80,299.

This invention relates to spring tools and more particularly to a device for supporting the springs of a certain type of automobile to relieve strain placed thereby on the shackle bolts so that these shackle bolts may be removed or replaced.

In the type of vehicle referred to, the springs extend above the axle paralleling the axle and are secured at their ends to shackle bolts carried by the axle. These springs, when released from their shackle bolts, have a tendency to move inwardly and downwardly and are difficult to properly align when new shackle bolts are to be inserted or to support when the old shackle bolts are to be removed.

An important and specific object of this invention is to produce a device for supporting the spring capable of relieving the tension of the spring which is brought to bear against the shackle bolt and of such construction that it is self-locking in its spring supporting position in which the tension upon the shackle bolt is relieved.

A still further object of the invention is to provide a device of this character which may be very readily and cheaply produced, which will be durable and efficient in service and a general improvement in the art.

These and other objects I attain by the construction shown in the accompanying drawings, wherein for the purpose of illustration is shown a preferred embodiment of my invention and wherein:

Figure 1 is a rear elevation showing a tool constructed in accordance with my invention applied to the axle of a vehicle in preparation to elevating the spring to release the shackle bolts, the spring being illustrated in dotted lines in the position which it assumes when unsupported and released from the shackle bolts;

Figure 2 is a view similar to that shown in Figure 1 but with the lever in its spring supporting position;

Figure 3 is a side elevation of the tool with portions broken away to show the construction thereof;

Figure 4 is a plan view thereof;

Figure 5 is an end view thereof;

Figure 6 is a section taken on the line 6—6 of Figure 3, the spring and axle being generally designated in dotted lines.

Referring now more particularly to the drawings, the numeral 10 generally designates a rear axle housing of the vehicle, 11 a spring shackle support, supported from the axle, 12 a spring which is engaged with this shackle bolt and 13 the differential housing of the axle which produces a shoulder 60 14 at the upper surface of the axle with which the tool coacts hereinafter in a manner to be described. As illustrated in dotted lines in Figure 1, the spring 12, when released from its shackle, has a tendency to 65 move inwardly and downwardly at its free ends.

In accordance with my invention, I provide a bar 15, the ends of which are downturned, as at 16 and 17 respectively and 70 shaped to conform to the shaping of the upper surface of the axle. The inner end is so constructed that it abuts against the shoulder 14 when in proper position upon the axle, thus providing a gauge for positioning the tool and at the same time providing means preventing longitudinal movement of the bar upon the axle. The bar 15 adjacent its outer end or that end bearing the downturned portion 17 is provided with 80 a transversely extending pivot 18, in the present instance shown as mounted in a block 19, riveted or otherwise secured to the bar 15, as at 20. The ends of this pivot project and upon one end thereof a short arm 21 of 85 a bell crank lever is pivoted at a point intermediate its ends. Upon the opposite end of the pivot, a link 22 is mounted.

A spring engaging bar 23 is provided, this bar being of sufficient width to extend 90 entirely across the bottom surface of the spring and having in its upper surface sockets 24 in which are arranged balls 25, the upper surfaces of which project above the upper surface of the plate to engage 95 the spring and prevent friction between the bar and spring. At its inner end, the spring engaging bar is provided with upwardly projecting ears 26 engaging opposite side faces of the spring to maintain the bar in 100 proper position with relation thereto. At its center, the plate 23 is provided with a pivot 27 which, as in the case of the pivot 18, is mounted in a block 28, riveted or otherwise secured to the bar 23, as at 29. 105 With the ends of this pivot are engaged the free extremities of the short arm 21 of the bell crank lever and the link 22.

In the use of the device, the bar 15 is placed in position upon the axle 10 with the 110

ends 16 in engagement with the shoulder 14. The long arm 30 of the lever is then engaged by the hand and moved toward the inner end of the bar 15 with the result that 5 the bar 23 is elevated and firmly engaged with the bottom of the spring, elevating the same to relieve the tension placed thereby upon the bolts of the shackle 31 connecting the spring to the spring support 11. At the 10 point where the shackle bolts are properly relieved and free in the openings through which they are directed, the lever has its long arm 30 substantially horizontally disposed and is automatically locked in adjusted 15 positions. It is pointed out at this time that two forces are working upon the plate 23, one to move this plate downwardly and the other to move the plate inwardly. In the proper supporting position, the pivot 20 27 is arranged slightly outwardly of a vertical plane including the axis of the pivot 18 with the result that the downward movement has a tendency to raise the long arm 30 of the lever while the inward movement 25 has a tendency to lower the same. Thus, these two forces counteract and maintain the plate stationary. With the spring thus held, the shackle bolts may be very readily removed and replaced without any attention 30 to the lever by the operator.

It will, of course, be understood that the construction hereinbefore set forth is obviously capable of a certain range of change and modification without materially departing from the spirit of the invention and I accordingly do not limit myself to such specific structure except as hereinafter claimed.

I claim:

1. A spring tool for supporting the springs 40 of vehicles in which the springs are directed transversely of the vehicle and overlie the axle thereof, said tool comprising an axle engaging bar for engaging the axle beneath the spring, a lever pivoted thereto and a 45 spring engaging bar for directly engaging the spring overlying the axle engaging bar and pivotally connected with the upper end of the lever.

2. A spring tool for supporting the springs 50 of vehicles in which the springs are directed transversely of the vehicle and overlie the axle thereof, said tool comprising an axle engaging bar, a lever pivoted thereto

and a spring engaging bar overlying the axle engaging bar and pivotally connected 55 with the upper end of the lever, said spring engaging bar having at its inner end ears spaced apart a distance equal to the thickness of the spring and adapted to engage the sides of the spring to maintain the bar 60 in alignment therewith.

3. A spring tool for supporting the springs of vehicles in which the springs are directed transversely of the vehicle and overlie the axle thereof, said tool comprising an axle 65 engaging bar, a lever pivoted thereto and a spring engaging bar overlying the axle engaging bar and pivotally connected with the upper end of the lever, the upper surface of the spring engaging bar being provided 70 with anti-friction elements for engagement with the spring.

4. A spring tool for supporting the springs of vehicles in which the springs are directed transversely of the vehicle and overlie the axle thereof and the axle is provided inwardly of the end of the spring with an enlargement forming a shoulder, said tool comprising an axle engaging bar shaped at 75 its under surface to conform to the shaping of the axle beneath the spring and adapted to engage against the shoulder of the axle with its inner end, a lever pivoted to the outer end of the bar to swing in a vertical plane and a spring engaging bar 80 overlying the axle engaging bar and pivotally connected to the upper end of the lever.

5. A spring tool for supporting the springs of vehicles in which the springs are directed transversely of the vehicle and 85 overlie the axle thereof, said tool comprising an axle engaging bar adapted to engage the axle beneath the spring and a spring engaging bar overlying the axle engaging bar and connected thereto by a link 90 pivoted to each thereof, said spring engaging plate having at its side edges ears for engaging the side edges of the spring to prevent displacement of the plate with relation to the spring and a lever operatively 95 engaged with said bars for shifting the spring engaging bar to move the same into 100 or out of engagement with the spring.

In testimony whereof I hereunto affix my signature.

ALBERT O. ERICKSON.
